UNITED STATES PATENT OFFICE.

EDWIN I. HEINSOHN, OF CLEVELAND, OHIO, ASSIGNOR TO THE GLASCOTE COMPANY, OF EUCLID, OHIO, A CORPORATION OF OHIO.

HEAT-EXCHANGING COIL.

Application filed January 26, 1925. Serial No. 4,695.

This invention relates to heat exchanging apparatus and more particularly to improvements in pipe coils for use in connection therewith.

5 In many industries, and particularly the food-manufacturing industries, it is desirable and practically necessary to use apparatus in which those portions that come in contact with the food, are coated with glass or 10 other vitreous material that will be neutral, chemically, to the food materials that come in contact therewith. Glass-coated apparatus is now commonly used in creameries, ice cream factories, and other plants that manufacture milk products and this type of apparatus is also now commonly used in plants 15 that manufacture such products as salad dressings, fruit syrups and canned foods.

In some of the apparatus, for the purposes 20 specified, it is desirable to have a coil, for a heating or cooling medium, submerged in the material for the purpose of raising or lowering its temperature quickly, and in all efforts that have been heretofore made, of 25 which I am aware, it has been found impracticable to satisfactorily coat a pipe coil with glass or other vitreous material and yet retain the coil in its desired shape. This is due to the fact that the coating material is 30 applied to the coil in the form of a powder which is fused and converted into an impervious coating by heating the coil to a very high temperature.

In thus coating a coil or other piece of apparatus with glass it is customary to heat it 35 in a furnace to a temperature of approximately 1800° F., and, at this temperature, steel and other available metals are so soft that, in efforts that have heretofore been 40 made to coat a coil of pipe with glass, the convolutions of the coil become badly distorted and the results have been wholly unsatisfactory.

It is one of the objects of this invention to 45 provide an improved form of pipe coil and method of making the same, that will result in a product that will have the desired shape and not be distorted and warped.

I have illustrated one form of my invention 50 in the accompanying drawings and in the following specification I disclose my improved method. In the drawings:

Figure 1 is a side elevation of a common form of helical pipe coil;

55 Fig. 2 is a side elevation of the same, on

a larger scale, with my invention applied thereto; and

Fig. 3 is an enlarged detail section on the line 3—3 of Fig. 2.

In practising my invention I take a coil, 60 such as that illustrated in Fig. 1, and weld spacers 10 in between the convolutions, these spacers being arranged in lines, as clearly shown in Fig. 3, and a sufficient number of 65 these lines of spacers being provided to support the convolutions against collapse when the coil is subsequently heated to the temperature of fusion of the coating. As shown in Fig. 2, there are six lines of the spacers 10, 70 equally spaced about the axis of the coil but 75 the number of lines of spacers necessary will be determined by the size of the pipe from which the coil is made and the diameter of the coil. It is important to have each row 80 of spacers in axial alignment so that the weight will be transmitted throughout the row without distorting any of the convolutions. The spacers are thoroughly welded 85 to the convolutions, as indicated at the points 11 in Fig. 3, and it is preferable to use tubular spacers in order to have the requisite strength and at the same time have the thickness of the metal of the spacers fairly uniform with that of the coil.

In coating articles with glass or other vitreous material it is advisable and practically essential to have the various parts that are to be coated, of substantially uniform thickness so that all of these parts will be brought 90 to the fusion temperature, of the coating, in approximately the same time and, for this reason, I prefer to use tubular spacers instead of solid rods.

With both ends of each spacer welded to the outer surface of the coil we would have 95 a certain amount of air trapped within each spacer and upon bringing the coil up to a temperature of 1800° F., the pressure would be greatly increased and would rise to such an amount as would result in bulging or distortion of the spacers when they are in the softened condition which results from heating the metal to this high temperature. In order 100 to relieve this pressure I vent the interior of each spacer, into one of the convolutions of the coil by means of a small opening, as indicated at 12. This opening does not detrimentally affect the subsequent use of the coil because, by using a single vent opening 12 for each spacer, there is no possibility of 110

short circuiting the heating or cooling medium through the spacers, from one convolution to the next.

In order to support the coil in the furnace I provide short legs or supports 13 which are preferably made of the same material as the spacers 10 and in alignment with the rows of the latter, as shown in Fig. 2. These supports 13 may be used for supporting the coil on a suitable surface, in the furnace, or the coil may be suspended in the furnace by means of the supports 13.

After the coil has been fabricated, as shown in Fig. 2, the coating material is applied to the entire surface of the coil, the spacers 10 and the supports 13, in the usual manner of applying this material to surfaces that are to be coated and the coil is then put into a suitable furnace and brought to the required temperature.

While I have referred, in this specification and also in the claims, to a glass-coated coil it will be understood that the invention is not limited to coatings that come within the technical term "glass". I use the term "glass-coated" in the broader sense in which it means any of the vitreous coatings that are commonly used in apparatus of the kind referred to.

Having thus described my invention, what I claim is:

1. As a new article of manufacture, a glass-coated pipe coil comprising a plurality of convolutions formed from a single length of pipe and having glass-coated spacers between the convolutions and integrally united therewith.

2. As a new article of manufacture, a glass-coated pipe coil comprising a plurality of convolutions arranged to form a continuous coil and having glass-coated tubular spacers between the convolutions and integrally united therewith.

3. As a new article of manufacture, a glass-coated pipe coil comprising a plurality of convolutions arranged to form a continuous passage through said coil and having glass-coated spacers between the adjacent convolutions and integrally united therewith, said

spacers being symmetrically arranged in a plurality of lines about the axis of the coil.

4. As a new article of manufacture, a glass-coated pipe coil comprising a plurality of convolutions arranged in series to form a continuous passage through said convolutions and having glass-coated tubular spacers between the adjacent convolutions and integrally united therewith, said spacers being arranged in a plurality of lines equally spaced about the axis of the coil.

5. As a new article of manufacture, a glass-coated pipe coil having glass-coated tubular spacers between the adjacent convolutions and integrally united therewith, said spacers being arranged in a plurality of lines equally spaced about the axis of the coil and there being openings in the coil through which the interior of each spacer is vented into one of the convolutions with which it is united.

6. As a new article of manufacture, a glass-coated pipe coil having glass-coated tubular spacers between the convolutions and integrally united therewith, and there being openings in the coil through which the interior of each spacer is vented into one of the convolutions with which it is united.

7. As a new article of manufacture, a glass-coated pipe coil comprising a plurality of convolutions spirally arranged in series to provide a continuous passage therethrough and having rows of glass-coated spacers between the convolutions and integrally united therewith, glass-coated supports on one of the end convolutions and integral therewith, and said supports being in alignment with said rows of spacers.

8. As a new article of manufacture, a glass-coated pipe coil having a single continuous passage therethrough and having rows of glass-coated tubular spacers between the convolutions and integrally united therewith, glass-coated tubular supports on one of the end convolutions and integrally united therewith, and said supports being in alignment with said rows of spacers.

In testimony whereof I affix my signature.

EDWIN I. HEINSOHN.
